[57] **CLAIM**

The ornamental design for the ice cap, as shown and described.

DESCRIPTION

FIG. 1 is a front elevational view of the ice cap showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a cross-sectional view thereof taken along line 7—7 of FIG. 5;

FIG. 8 is a front elevational view of an alternative embodiment thereof;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof; and,

FIG. 14 is a cross-sectional view thereof taken along line 7—7 of FIG. 12.

The broken line showing of the word "logo" in FIGS. 1 and 8 is for illustrative purposes only and forms no part of the claimed design.
